US00D691013S

(12) **United States Design Patent**
Campbell et al.

(10) **Patent No.:** **US D691,013 S**
(b4) **Date of Patent:** ** **Oct. 8, 2013**

(54) **SANDING PAD FOR RECIPROCATING SAW**

(75) Inventors: **Doug Campbell**, Overland Park, KS (US); **Ryan Campbell**, Overland Park, KS (US)

(73) Assignee: **SM Products, LLC**, North Kansas City, MS (US)

(**) Term: **14 Years**

(21) Appl. No.: **29/421,166**

(22) Filed: **Jun. 4, 2012**

(51) **LOC (9) Cl.** **08-03**

(52) **U.S. Cl.**

USPC **D8/70**

(58) **Field of Classification Search**

USPC D8/61-70; D15/124, 126, 138; 451/47, 451/56, 324, 344, 356, 443, 541, 548-551; D32/15, 17, 19, 50; D25/138

See application file for complete search history.

(57) **CLAIM**

The ornamental design for a sanding pad for reciprocating saw, as shown and described.

DESCRIPTION

FIG. 1 is a front perspective view of the sanding pad;
FIG. 2 is a front elevational view of the sanding pad of FIG. 1;
FIG. 3 is a rear elevational view of the sanding pad of FIG. 1;
FIG. 4 is a top plan view of the sanding pad of FIG. 1;
FIG. 5 is a bottom plan view of the sanding pad of FIG. 1;
FIG. 6 is a right side elevational view of the sanding pad of FIG. 1; and,
FIG. 7 is a left side elevational view of the sanding pad of FIG. 1.

1 Claim, 3 Drawing Sheets
